John A. Mathes

UNITED STATES PATENT OFFICE.

JOHN A. MATHES, OF SAN DIEGO, CALIFORNIA.

KEROSENE VAPORIZER.

Application filed September 27, 1920. Serial No. 413,040.

My invention relates to kerosene vaporizing air mixing means for internal combustion engines in which the kerosene or other liquid hydrocarbon is converted into a dry 5 superheated vapor in vaporizing tubes heated by the hot exhaust gases from the engine coming in contact with the outer surface of said vaporizing tubes.

The hot exhaust gases enter a jacket 10 formed around the vaporizing tubes and circulate around the tubes to heat them to the vaporizing temperature of the liquid fuel contained in the vaporizing tubes.

A further object is to provide a simple air 15 and fuel vapor mixer, which is formed by the usual intake manifold with a pipe extension having an open end to form the inlet mixing tube of the air and fuel vapor mixer.

The air and vapor mixer is provided with 20 an opening in the side to receive the heated vapor from the secondary vaporizing tube where it is thoroughly mixed with atmospheric air in correct proportions for perfect combustion.

25 It is further provided that the air and vapor mixer is positioned at the side of and in close proximity to the exhaust gas manifold and to the exhaust gas jacket and in heat receiving relations thereto.

30 The exhaust gas jacket is located at the side of the engine cylinders as near the exhaust manifold as practical.

By positioning the exhaust gas jacket which contains the vaporizing tubes and the 35 air and vapor mixer where the vapor is mixed with air at the side and in close proximity to the engine exhaust manifold, I am enabled to maintain the vaporized hydrocarbon vapor at a temperature above the 40 condensing temperature of the mixed vapor that is being conveyed to the engine cylinders.

The vaporizing tubes are both inclined at a considerable angle from the inlet on the 45 upper end down to the outlet of the lower ends. This inclination is for the purpose of causing the small quantity of liquid fuel that is caused to enter the upper tube from the oil supply pipe, when the supply valve 50 is opened momentarily preparatory to starting, to pass down over the surface of the secondary or lower vaporizing tube, the vaporizing tube having been previously heated by the electric heating element.

A further object of having the vaporizing 55 tubes inclined downward is to prevent the tubes from filling at any time with any considerable quantity of liquid as would be the case with tubes located horizontally.

To promote a quick starting of a cold 60 engine with the use of the regular kerosene or other hydrocarbon contained in the main supply tank and conducted through the same channels as the main supply of liquid fuel, 65 is one advantage of my invention which is accomplished by having the secondary vaporizing tube positioned in an inclined position from the inlet down to the outlet and a limited quantity of oil caused to flow down over a large heated surface of vaporizing 70 pipe, and having a large open unobstructed outlet into the inlet end of the air and vapor mixer and then only a short distance for this small charge of mixed vapor to travel to the engine cylinders. The heating of the 75 vaporizer for this initial starting is accomplished by the electric heating element shown or other suitable means.

After the initial heating, as explained, the 80 exhaust gases in the exhaust gas jacket make the heating of the tubes continuous and automatic, and the electric current is turned off.

In the claims the vaporizing tube 4 is referred to as the primary vaporizing tube 85 and tube 13 as the secondary vaporizing tube.

With these objects in view, my invention is embodied in preferable form in the construction and arrangement hereinafter described and illustrated in the accompanying 90 drawing.

The drawing is a diagrammatical view in vertical section of the complete device.

The form of device shown in the drawing 95 consists of a jacket 1 completely enclosing the vaporizing tubes 4 and 13. Jacket 1 is formed of one integral casing which is imperforate save at the inlet 2 and outlet 3; forming an inlet and an outlet for the exhaust gases from the exhaust gas manifold, 100 not shown in the drawing, which allow the exhaust gases to circulate freely around the vaporizing tubes to maintain them at the vaporizing temperature as long as the engine is in operation.

105 Formed as a part of vaporizing tube 4 is valve body 4^a having valve stem 11 which is adapted to seat in the orifice seat 12, while

lever arm 10 actuates valve stem 11. The orifice formed at seat 12 serves as an outlet for the heated vapor of vaporizing tube 4 when the engine exhaust is heating the liquid fuel to a vapor in vaporizing tube 4 and serves as an outlet for the small quantity of liquid fuel when the supply valve 8 is opened momentarily by valve lever 9 for the initial starting of the vaporizer, the tube 13 having previously been heated by the electric heating element 15.

The control of the liquid fuel supply flowing through pipe 7 from a supply tank by valve 8, has only secondary importance in regulating the proportions of kerosene vapor to air. The valve 8 is adjusted only roughly, there being at all stages of adjustment an opening allowing a surplus of liquid fuel. The opening at orifice 12 allows only sufficient vapor to escape as to give the correct proportion for the air flowing in the air and vapor mixer, and thereby creates a back pressure that automatically regulates the flow of liquid into vaporizing tube 4 through valve 8, in other words, the valve 11 controls the amount of liquid that passes through valve 8.

Formed as a part of the lower end of vaporizing tube 4 is tube 13^b and sleeve 14. Sleeve 14 serves as a means of attaching tube 13 to 13^b and tube 4 and with an insulated joint at the upper end of vaporizing tube 13. At the lower end of tube 13 is another insulated joint 14^a formed as a part of sleeve 13^a, both insulated joints serving to insulate the vaporizer 13 from metal contact that would dissipate the heat derived from the electric heating element 15 when heating the tube 13 preparatory for the initial starting. The secondary vaporizing tube 13 is made relatively smaller than primary vaporizing tube 4 to conserve the heat required for the initial starting, the short tube 13^a having outlet 23 serves as a support for the insulated joint 14^a and as a conduit for the vapor from tube 13.

Formed in the lower side of jacket 1 is the insulating bushings 16 and 16^a through which the electric terminal wires pass to the electric heating element.

Formed as an end to the electric heating element chamber 17 is wall 1^a which also serves as a support for sleeve 14.

The electric element chamber 17 has front and back side walls, not shown, and has its top side closed by the lower wall of tube 13, making the chamber 17 imperforate save for the entering openings for the electric wires, which arrangement keeps the exhaust gases from coming in contact with the electric heating element.

In the upper end of the vaporizing tube 4 is placed a light wire mesh, 5, which serves as a filler to cause part of the liquid fuel to adhere by capillary attraction and remain in

the upper end of the vaporizing tube during the operation of the vaporizer, preventing pulsation of the vapor supply and the liquid supply, and the wire serves to retain a small part of the initial charge of cold oil that passes through the wire on its way to the lower vaporizing tube 13, when the engine is started from a cold state with the electric element. The secondary vaporizing tube 13 is small in diameter to insure quick starting and economy in use of electric current.

Oil supply valve 8 has a spring seat head, not shown, attached to the valve stem which will open upwardly and allow a release of pressure in the chamber of vaporizing tube 4 when the valve 8 and valve 11 are closed on stopping the engine, which pressure would be caused by the heat retained in the heat exhaust gas jacket 1 expanding the vapor contained in tube 4.

In practice other auxiliary devices may be incorporated with this apparatus, but their absence does not materially effect the successful working of the device.

Vaporizing tube 13 terminates at its lower end 13^a in an opening in the side of the cold air intake end of the air and fuel vapor mixing chamber 20 formed by casing 18.

Butterfly valve 19 is positioned in air and vapor mixer 20 at a point above the outlet of the vaporizing tube 13^a.

The upper end of the air and vapor mixing tube 20 is bent inwardly and back of the hot exhaust gas jacket 1, for the purpose of having the air mixer in heat receiving relation to the jacket 1 and to the exhaust manifold of the engine, not shown in drawing.

Cap 6 on tube 4 has threaded engagement to facilitate removal of wire filler 5.

It is thus seen that with this construction and arrangement that the air after entering the mixing tube at 21 mixes with the oil vapor discharged from 23 and goes to the engine cylinders through conduit 22. Thus all parts of the air and vapor mixer are in intimate relations with the hot zone of the exhaust manifold and the exhaust gas jacket, which arrangement prevents condensation of the mixed air and vapor.

In this invention the air and vapor mixer is considered as the chamber from the air intake to the engine cylinder inlet ports, which is not necessarily constructed in the form of the usual intake manifold. The upper portion of air and vapor mixer is not shown in drawing.

In the operation of this device, before the engine is given the usual turn over for starting, the electric switch controlling the current for the heating element is turned on and after a half minute of heating the vaporizing tube 13 the hand throttle lever is turned to wide open and quickly closed again. This operation has discharged a

small quantity or liquid fuel into the upper end of the vaporizing tube 4 where a portion adheres to the wire filler 5 and a portion passes quickly down and out the opening 12 into vaporizing tube 13 and down over the heated surface of the tube which is heated by the electric element 15, immediately after closing the valve 8, which is manipulated by the hand throttle lever, the engine is turned over for starting in the usual way and draws in sufficient air to mix with the small quantity of vapor that is discharged from tube 13 into the chamber of tube 20 of the air and vapor mixer, the butterfly valve 19 standing at the starting position, or partly open, even when the valve 8 and orifice 12 are closed, as they would be at this stage of the operation, which permits sufficient vapor mixture to pass valve 19 to give the engine a few explosions. Now the operator observes that the engine has started and shifts the hand throttle lever (not shown) to open the three valves 8, 11, and 19 respectively a limited amount, which causes the vapor that has formed in the tube 4 from the heat of the exhaust gas of the few first explosions and also the heat of the electric element to supply sufficient heat to continue the operation. The process of heating the tubes and the mixing of the vapor with air is now continuous and automatic.

After the engine is insured a good start, as stated above, the electric heating element is turned off and the operation of the engine from that time until the next starting operation is in the usual way.

Having thus described my invention what I claim is:—

1. A kerosene vaporizer comprising a casing having an inlet and an outlet for a heating agent, an air and vapor mixing chamber, a primary vaporizing tube for vaporizing kerosene supported in said casing having a valve controlled inlet at one end and a valve controlled outlet at the other end, and a secondary vaporizing tube held in communication with the valve controlled outlet of said primary vaporizing tube and connected in open unrestricted communication with said air and vapor mixing chamber.

2. A kerosene vaporizer comprising a casing having an inlet and an outlet for a heating agent, an air and vapor mixing chamber, a primary vaporizing tube for vaporizing kerosene supported in said casing having a valve controlled inlet at one end and a valve controlled outlet at the other end, a secondary vaporizing tube held in communication with the valve controlled outlet of said primary vaporizing tube and connected in unrestricted open communication with said air and vapor mixing chamber, and held in a downwardly inclined position relative to said primary vaporizing tube.

3. A kerosene vaporizer comprising a cas-

ing having an inlet and an outlet for a heating agent, an air and vapor mixing chamber, a primary vaporizing tube for vaporizing kerosene supported in said casing having a valve controlled inlet at one end and a restricted outlet at the other end, a secondary vaporizing tube held in communication with the outlet of said primary vaporizing tube and connected in unrestricted open communication with said air and vapor mixing chamber, and held in a downwardly inclined position relative to said primary vaporizing tube, and an electrical heating element located in said casing adjacent to said secondary vaporizing tube.

4. A hydrocarbon vaporizer comprising a casing having an inlet and an outlet for exhaust gas, two downwardly inclined vaporizing tubes supported in said casing, the upper end of the primary vaporizing tube having an inlet for the liquid fuel and the lower end having a valve controlled outlet communicating with the upper end of the secondary vaporizing tube, the outlet of said secondary vaporizing tube is unobstructed, and an air and vapor mixing chamber connected to the open end of said secondary vaporizing tube.

5. A kerosene vaporizer comprising a casing having an inlet and an outlet for exhaust gas, two downwardly inclined vaporizing tubes supported in said casing, the upper end of the primary vaporizing tube having a valve controlled inlet and the lower end having a valve controlled outlet communicating with the upper end of the secondary vaporizing tube, the outlet of which is unobstructed.

6. A kerosene vaporizer comprising a casing having an inlet and an outlet for exhaust gas, two downwardly inclined vaporizing tubes supported in said casing, the upper end of the primary vaporizing tube having a valve controlled inlet and the lower end having a valve controlled outlet communicating with the upper end of the secondary vaporizing tube, the outlet of which is unobstructed, and an electrical heating element located in said casing adjacent to said secondary vaporizing tube.

7. A kerosene vaporizer comprising a casing having an inlet and an outlet, two downwardly inclined vaporizing tubes supported in said casing, the upper end of the primary vaporizing tube having a valve controlled inlet and the lower end having a valve controlled outlet communicating with the upper end of the secondary vaporizing tube, the outlet of the secondary vaporizing tube being unobstructed and the diameter of which being reduced relative to said primary vaporizing tube.

8. A kerosene vaporizer comprising a casing having an inlet and an outlet, two downwardly inclined vaporizing tubes supported

in said casing, the upper end of the primary vaporizing tube having a valve controlled inlet and the lower end having a valve controlled outlet communicating with the upper end of the secondary vaporizing tube, the diameter of which being reduced relative to said primary vaporizing tube, and an air and vapor mixing chamber connected thereto at its lower end.

In testimony whereof, I have signed my name to this specification this 24th day of September 1920.

JOHN A. MATHES.
